US00D925706S

(12) **United States Design Patent** (10) **Patent No.:** **US D925,706 S**
(45) **Date of Patent:** **** Jul. 20, 2021**

(54) **FAUCET BODY**

(71) Applicant: **Qiwen Liu**, Hunan (CN)

(72) Inventor: **Qiwen Liu**, Hunan (CN)

(73) Assignee: **SHENZHEN MINGSHENG
KITCHEN EQUIPMENT CO., LTD.,**
Shenzhen (CN)

(**) Term: **15 Years**

(21) Appl. No.: **29/771,026**

(22) Filed: **Feb. 19, 2021**

(51) LOC (13) Cl. **23-01**

(52) U.S. Cl.

USPC **D23/241**

(58) **Field of Classification Search**

USPC D23/241-243, 249

CPC F16K 19/006

(57) **CLAIM**

The ornamental design for a faucet body, as shown and described.

DESCRIPTION

FIG. 1 is a perspective view of a faucet body showing my new design;

FIG. 2 is another perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is an enlarged perspective view thereof.

The broken lines throughout the drawing figures depict portions of the faucet body that form no part of the claimed design.
